INVENTOR.

United States Patent Office.

E. W. GRIFFIN, OF PEPPERELL, ASSIGNOR TO HIMSELF AND F. S. BROWN,
OF CAMBRIDGE, MASSACHUSETTS.

Letters Patent No. 99,310, dated February 1, 1870.

IMPROVEMENT IN THRESHING-MACHINE.

The Schedule referred to in these Letters Patent and making part of the same.

To all whom it may concern:

Be it known that I, E. W. GRIFFIN, of Pepperell, in the county of Middlesex, and State of Massachusetts, have invented Improvements in Hand Threshing-Machines; and I hereby declare that the following is a full and exact description of the same, reference being had to the accompanying drawings, and to the letters of reference thereon, making part of this specification, of which—

Figure 1 is a side elevation of the machine, and
Figure 2 is a cross-section of the same.

The letter A, represents the frame or body of the thresher;

B, the top or cover;
a a, the plates or disks, with teeth a' a', &c.;
b b, &c., the serrated beaters;
c, the corrugated hopper or feed-box;
d, the crank, and d', the axle of the wheel;
e and f, geared wheels; and

g g, springs upon the bolts, attaching the disks.

The machine is for threshing grain, grasses, beans, and like products, by hand.

The invention consists in improvements upon the same, for the more effectual working thereof, and are explained as follows, the accompanying drawings exhibiting the exterior and interior parts thereof:

A represents the frame with two sides, joined by braces at the top and bottom, and the ends of the frame are open, as seen in the two figures. The same is made of wood or any suitable material.

B represents the top or cover, which may be removed at pleasure, when not in use.

a a are plates or disks, made concavo-convex, or plano-convex, or with two plain surfaces, with teeth set in the convex surfaces, or surfaces opposite each other, as seen in fig. 2. These plates or disks are pendulously attached to the sides of the frame by a bolt, screw, and nut; and between the disks and the sides of the frame, and around the bolt, are spiral springs g g. These disks are so hung or attached to the frame, that pressure upon the teeth and surfaces will cause them to spring back or yield to the pressure. The teeth are made conical, and are represented in both figures in the drawings.

The fliers or beaters b b, &c., are made of wood or metal, and are serrated, as seen in said figures.

This construction of the beaters more effectually performs the threshing than plain beaters, in combination with the disks. It also, in combination with the toothed disks, causes the straw to pass through better, when in wads, occasioned by too great quantity of feed.

The feed-box e is corrugated or serrated in that part of it within the frame A.

The advantage of this form is this: The effect of the blows of the serrated beaters is to draw the straw toward the right side of the feed-box, and the corrugated bottom will tend to counteract this.

The beaters are inserted into a hub upon an axle, like a wheel, and motion is communicated by means of the geared wheels f, situated on the axle d', and e, situated on the crank-shaft d, which is moved by hand.

Fig. 2 clearly indicates the position and construction of the various parts of the machine.

To the general form of the machine, I make no claim; but the improvements, viz, the toothed disks, combined and arranged with other parts of the machine, the serrated beaters, and the feed-box corrugated, the same being combined and arranged with the other parts of the machine, are new and useful inventions; and

What I claim as my invention, and desire to secure by Letters Patent, is—

1. The serrated beater b, constructed and arranged upon the hub and axle d', in combination with the frame A, the crank d, and the disks a a, all substantially operating in the manner and for the purpose set forth.

2. The construction and arrangement of the toothed plate or disk a, with its spring-device and attachment to the frame A, and in combination with the said frame and the beaters b b, &c., all operating substantially in the manner and for the purpose described.

3. The corrugated feed-box e, in combination with the parts of the machine, viz, the frame A, the beaters b b, &c., and the disks a a, operating for the purpose specified.

E. W. GRIFFIN.
